UNITED STATES PATENT OFFICE

JOSEPH A. SEISBERT, OF CAMDEN, NEW JERSEY

WASHING COMPOUND

No Drawing.

Application filed October 19, 1928. Serial No. 318,649.

My invention relates to new and useful improvements in a washing compound and the process of making the same, and has for one of its objects the commercial production at a reasonable cost, of a washing compound which will possess highly desirable qualities and when used, will form a water soluble emulsion with dirt, oil, grease and other substances which it is desirable to remove from clothes and household articles.

Another object of the invention is to produce a washing compound which will not harm or damage fabrics, wool or metal and therefore can be used for cleansing the finest articles and the washing process can be carried out in wooden or metal receptacles.

A further object of the invention is the employment of a new process for the production of a washing compound which consists in first mixing together given quantities of trisodium phosphate, neutral ground powdered soap and borax, then adding a quantity of denatured alcohol and any desired perfume and finally adding a second quantity of denatured alcohol, thus producing an intimately blended compound without producing a mushy or caky mass.

With the above named objects in view, my invention and process carried out on a commercial scale embodies the following successive progressive steps:—

Forty pounds of trisodium phosphate; twelve pounds of neutral ground powdered soap; and eight pounds of borax are placed in a mixing machine and said ingredients thoroughly mixed, say by operating the machine for about five minutes, then three ounces of bluing is added to the previously mixed ingredients after which two ounces of denatured alcohol and about one ounce of a suitable or desirable perfume dissolved in said alcohol are added to the mixture. The mass is again agitated until the bluing and the mixture of alcohol and perfume are thoroughly distributed which may be accomplished by running the mixing machine for approximately another five minutes. This having been done, an additional four ounces of denatured alcohol is added to the mass and said mass again agitated for approxi-

mately another five minutes or until all of the ingredients are thoroughly and intimately mixed together.

The alcohol not only acts as a carrier for the perfume but also dissolves the bluing and acts as a carrier for the latter so that it will become thoroughly distributed, evenly throughout the mixture.

As the alcohol quickly evaporates, it takes but a relatively few minutes for it to pass off and leave the mixture practically dry and therefore such mixture will not be mushy or liable to cake.

This is the only method or way in which the perfume and bluing can be added to the mixture so that the compound is ready for packing immediately after the mixing operations have been completed. By using any liquid other than alcohol, such as water, the mixture will form a mushy mass and when dry will cake so that in either case, it is unfit to be run into the packing machine until after it has dried out and been crushed or otherwise broken up.

The trisodium phosphate mentioned herein is wholly different from the ordinary phosphate of sodium or sodium phosphate generally sold by druggists for medicinal purposes and is an exceedingly effective water softener. Said trisodium phosphate is harmless to a person's hands and most, if not all, fabrics but has a powerful affinity for grease, oils and like substances and with said substances immediately forms an emulsion so that they are removed from any goods which may be immersed in water to which the compound has been added.

In actual use a suitable quantity of the compound is added to either hot or cold water and the articles to be washed are soaked for a short time and then occasionally stirred and finally rinsed in clear water to remove the soap and excess bluing after which said articles may be wrung out and hung up for drying.

From the foregoing it will be noted that I have provided a highly efficient washing compound for use in the home laundry which does not have to be dissolved and while it

contains no harmful chemicals, it acts as a germicide deodorant.

While I have outlined the successive progressive steps of the process and set forth the specific quantities of the ingredients most desirable, it is obvious that they may be slightly altered or added to without departing from the spirit of my invention.

Having thus fully described my invention, 10 what I claim as new and useful is:—

1. The process of producing a washing compound which consists of mixing together quantities of trisodium phosphate, powdered soap and borax, then adding and thoroughly mixing therewith a coloring matter, next adding and mixing therewith a quantity of perfume dissolved in alcohol and lastly adding an additional quantity of alcohol to dissolve the previously added coloring matter 15

20 and again mixing all of the ingredients.

2. The process of producing a washing compound which consists of mixing together forty pounds of trisodium phosphate, twelve pounds of ground powdered soap, eight 25 pounds of borax, next adding three ounces of bluing and again mixing the ingredients, next adding a perfume dissolved in alcohol and again mixing the ingredients and lastly adding an additional quantity of alcohol and 30 agitating all the ingredients until thoroughly mixed.

In testimony whereof, I have hereunto affixed my signature.

JOSEPH A. SEIBERT.
